MERCHANDISING DISPLAY STAND

Robert H. Ensign, Bronxville, N.Y., assignor to Scripto,
Inc., a corporation of Georgia

Filed June 4, 1959, Ser. No. 56,203

Term of patent 14 years

(Cl. D80—9)

Fig. 1 is a perspective view of a merchandising display stand embodying my new design, the broken-line representations being for purposes of illustration only.

Fig. 2 is a side elevational view thereof; and

Fig. 3 is a top plan view thereof.

I claim:

The ornamental design for a merchandising display stand, as shown and described.
